PRINTING PLATE CLAMP

Howard M. Barber, Pawcatuck, Conn., assignor to
 C. B. Cottrell & Sons Company, Westerly, R. I.,
 a corporation of Delaware

Application October 2, 1942, Serial No. 460,501

7 Claims. (Cl. 101—387)

In the use of printing plate clamps of the type where a screw is employed for clamping the cylinder and nut to the plate support, as, for instance, a cylinder, in their plate clamping position along a groove in the cylinder, it has been found that at high speeds it is difficult to maintain these clamps in their operative positions due to the strain of holding the plates on the cylinder at said high speeds. It has also been found that the clamps not only break due to the excessive strain thereon under high speeds but that they also break due to the fact that the clamp screws receive directly the shocks of the blows delivered by the pressmen against the nuts to force the clamps along the grooves into their plate clamping positions, thus causing a shearing strain on the clamp screws.

The object of my invention is to provide means for relieving this shearing or side strain on the clamp screws when forcing the clamps into their operative position, and thus make it possible to successfully use this type of clamp in high speed presses; said strain on the screws being eliminated by the provision of coating surfaces of various forms between the plate hooks and nuts, for absorbing the blows on the nuts and thus preventing the effect of the blows being transferred to the clamp screws.

Practical embodiments of my invention are represented on an enlarged scale in the accompanying drawings in which

Fig. 1 represents a detail side view of a grooved cylinder with one form of printing plate clamp engaging one curved side edge of the printing plate;

Fig. 2 represents a section taken in the plane of the line II—II of Fig. 1;

Fig. 3 represents a section taken in the plane of the line III—III of Fig. 2;

Fig. 4 represents an end view of the plate clamp nut;

Fig. 5 represents a bottom plan view of the plate clamp hook;

Fig. 6 represents an end view of the hook; and

Fig. 7 represents a side view of the hook.

Fig. 8 represents a section similar to Fig. 3, showing a second form of clamp;

Fig. 9 represents a view of the nut;

Fig. 10 represents an end view of the same;

Fig. 11 represents a bottom plan view of the hook;

Fig. 12 represents an end view of the same; and

Fig. 13 represents a side view of the hook.

Fig. 14 represents a section similar to Fig. 3, showing a third form of clamp;

Fig. 15 represents a side view of the nut;

Fig. 16 represents an end view of the same;

Fig. 17 represents a bottom plan view of the hook;

Fig. 18 represents an end view of the same; and

Fig. 19 represents a side view of the hook.

Fig. 20 represents a view similar to Fig. 1, showing the form of clamp illustrated in Figs. 14 to 19 inclusive, in which the hook is flat instead of curved, rendering it adaptable for engaging a straight edge of the curved printing plate;

Fig. 21 represents a bottom plan view of the hook; and

Fig. 22 represents a side view of the same.

Fig. 23 represents a detail side view of a grooved cylinder with a fourth form of clamp in which the hook is curved for engaging a curved side edge of the printing plate;

Fig. 24 represents a section taken in the plane of the line XXIV—XXIV of Fig. 23;

Fig. 25 represents a section taken in the plane of the line XXV—XXV of Fig. 24;

Fig. 26 represents an end view of the plate clamp nut;

Fig. 27 represents a bottom plan view of the plate clamp hook;

Fig. 28 represents an end view of the same;

Fig. 29 represents a side view of the hook; and

Fig. 30 represents a side view of the hook in its flat form for engagement with a straight edge of the printing plate.

The printing plate support which is herein shown as a cylinder, is denoted by 1, and one of its usual spiral grooves by 2, which groove may be of any well known or approved cross sectional shape.

The curved printing plate is denoted by 3, one of its curved beveled edges by 4 and one of its straight beveled edges by 5.

The plate clamp comprises the nut 6, the plate hook 7 and the clamp screw 8. In the embodiments shown in Figs. 1 to 22 inclusive the plate hook 7 is shown as provided with a guide member 9 which is provided with parallel side edges 10, 10, slidably engaging the side walls of the groove 2 and thus forming an extended bearing for guiding the plate hook 7 along the groove with the nut 6, into and out of engagement with either the curved edge 4 or the straight edge 5 of the printing plate 3, as the case may be. It will be noted that the guide member 9 projects

under the beveled edge of the plate and forms together with the beveled edge of the plate hook an angular recess for receiving the beveled edge of the plate, thereby preventing the hook from riding up thereon.

It will be understood that the clamp screw 8 passes freely through the plate hook 7 and its guide member 9 into threaded engagement with the nut 6.

This nut 6 in all of the embodiments illustrated is shown as having a shallow recess 11 adapted to receive the guide member 9 of the plate hook 7 when the parts of the clamp are assembled.

Coacting surfaces are provided on the plate hook guide member 9 and the nut 6 for preventing the plate hook from exerting a side strain on the clamp screw 8 when endwise force such as repeated blows is directed against the clamp nut 6 to drive the clamp along the cylinder groove into engagement with the curved or straight beveled edge of the printing plate 3.

In the embodiment shown in Figs. 1 to 7 inclusive the uprising inner wall of the shallow recess 11 in the nut 6, which houses the guide member 9 of the plate hook 7, is shaped to form two angular surfaces 12, 13 which coact with corresponding angular surfaces 14, 15 of the adjacent end wall of the said guide member; the coacting surfaces 12 and 14 being parallel with the back edge of the plate hook and the coacting surfaces 13 and 15 being at right angles to the cylinder groove 2.

In the embodiment shown in Figs. 8 to 13 inclusive the uprising inner wall of the shallow recess 11 in the nut 6 forms a plane surface 16 which coacts with a corresponding plane surface on the hook guide member 9.

In the embodiment shown in Figs. 14 to 19 inclusive the uprising inner wall of the shallow recess 11 in the nut 6 has a curved surface 17 which coacts with a corresponding curved surface 18 at the adjacent end of the guide member 9, said curved surfaces being concentric with the clamp screw 8 so that the hook may properly seat against the edge of the printing plate even though the spiral groove 2 in the cylinder is not milled at exactly forty-five degrees.

In the embodiment shown in Figs. 20 to 22 inclusive the plate hook is shown as straight instead of slightly curved so as to facilitate the clamping of the straight beveled edge 5 of the plate lengthwise of the cylinder. In these Figures 20 to 22 inclusive the coacting surfaces are of the form illustrated in Figs. 14 to 19 inclusive.

In the embodiment shown in Figs. 23 to 29 inclusive the nut 6 is shown as having a circular recess 19 concentric to the clamp screw 8 for snugly receiving the circular concentric guide member 20 of the curved hook 7, thereby permitting the hook to be rotated on the nut to engage either one of the opposite curved edges 4 of the curved plate 3. It is understood that the side walls of the recess and guide member form the coacting surfaces which prevent the shock of the blows on the nut 6 being transmitted to the clamp screw 8. In Fig. 30 the plate hook 7 is shown as flat for engaging one of the straight edges 5 of the printing plate 3.

In all of the embodiments the coacting surfaces of the plate hook and nut are so located that they, rather than the clamp screws, will receive the force of any blows against the nuts for driving the clamps into their engagement with the printing plates.

While I have shown the printing plate clamps as mounted on a cylindrical support, it is obvious that these clamps could be readily adapted without invention for use on flat supports.

5 The clamps shown in Figs. 1 to 13 inclusive and described but not claimed herein form the subject matter of my copending application filed June 12, 1943, Serial No. 490,563.

It is evident that various changes may be resorted to in the construction, form and arrangement of the several parts without departing from the spirit and scope of my invention, and hence I do not intend to be limited to the particular embodiments herein shown and described, but 10 what I claim is:

1. In a plate clamp adapted to be moved along a grooved support into engagement with an edge of a printing plate, a hook, a nut slidable in said grooved support and a clamp screw passing through the hook into threaded engagement with the nut, said hook and nut having curved coacting surfaces concentric with the clamp screw for preventing the hook from exerting side strain on the screw when the nut is subjected to endwise force and also to permit the hook to be properly seated against the edge of the printing plate.

2. In a plate clamp adapted to be moved along a grooved support into engagement with an edge of a printing plate, a hook, a nut slidable in said grooved support and a clamp screw passing through the hook into threaded engagement with the nut, said hook having a circular element concentric with the clamp screw, and said nut having a circular recess for receiving said circular element for permitting the rotative adjustment of the hook and preventing the hook from exerting side strain on the screw when the nut is subjected to endwise force.

3. In a plate clamp adapted to be moved along a grooved support into engagement with an edge of a printing plate, a hook provided with a guide member slidable in a groove of said support, a nut also slidable in said groove, and a clamp screw passing through the hook and guide member into threaded engagement with the nut, said guide member and nut having curved coacting surfaces concentric with the clamp screw and arranged to prevent the hook from exerting side strain on the screw when the nut is subjected to endwise force and also to permit the hook to be properly seated against the edge of the printing plate.

4. In a plate clamp adapted to be moved along a grooved support into engagement with an edge of a printing plate, a hook provided with a guide member slidable in a groove of said support, a nut also slidable in said groove and a clamp screw passing through the hook and guide member into threaded engagement with the nut, said nut having a recess for receiving the guide member and also having a curved shoulder concentric with the clamp screw and which coacts with the guide member to prevent the hook from exerting side strain on the screw when the nut is subjected to endwise force and also to permit the hook to be properly seated against the edge of the printing plate.

5. In a plate clamp adapted to be moved along a grooved support into engagement with an edge of a printing plate, a hook provided with a guide member slidable in a groove of said support, a nut also slidable in said groove, and a clamp screw passing through the hook and guide member into threaded engagement with the nut, said

guide member and nut having circular coating surfaces concentric with the clamp screw for rotatively mounting the hook on the nut and for preventing the hook from exerting a side strain on the clamp screw when the nut is subjected to endwise force.

6. In a plate clamp adapted to be moved along a grooved support into engagement with an edge of a printing plate, a plate hook provided with a guide member having two diagonal parallel sides connected by a curved end, a nut having a shallow recess with a curved end for housing the guide member, and a clamp screw passing through the hook and recess into threaded engagement with the nut, the coating curved ends of the shallow recess and guide member being concentric with the clamp screw for preventing the hook from exerting a side strain on the screw

when the nut is subjected to endwise force and also to permit the hook to be properly seated against the edge of the printing plate.

7. In a plate clamp adapted to be moved along a grooved support into engagement with one edge of a printing plate, a plate hook provided with a circular guide member, a nut having a circular recess for snugly housing the circular guide member, and a clamp screw passing through said hook and centrally through said guide member and recess into threaded engagement with the nut, the circular coating side walls of the guide member and recess serving to rotatively mount the hook on the nut and to prevent the hook from exerting a side strain on the clamp screw when the nut is subjected to endwise force.

HOWARD M. BARBER.
